G. L. COMLOSSY

PACKING GUIDE FOR FRUIT AND VEGETABLE CONTAINERS

Filed March 3, 1923

UNITED STATES PATENT OFFICE.

GEORGE L. COMLOSSY, OF TOLEDO, OHIO.

PACKING GUIDE FOR FRUIT AND VEGETABLE CONTAINERS.

Application filed March 3, 1923. Serial No. 622,632.

To all whom it may concern:

Be it known that I, GEORGE L. COMLOSSY, a citizen of the United States, and a resident of Toledo, in the county of Lucas and State of Ohio, have invented certain new and useful Improvements in Packing Guides for Fruit and Vegetable Containers, of which the following is a specification.

My present invention relates generally to the packing of fruit, vegetable and other containers, for instance fruit boxes, within railway freight cars, where it is essential for the preservation of the commodity in transit, that the containers be packed sufficiently tight to prevent jostling or jolting of the containers against one another.

In refrigerator cars for example fruit boxes are packed endwise upstanding, in longitudinal and transverse rows, commencing from the ends of the cars and working toward the center opposite the doorway and in this packing operation the boxes are separated in transverse rows by transverse strips with the object in view of leaving at the center of the car a transverse space in which a single row of boxes will fit snugly and tightly. In view however of the varying bulge of the sides of the boxes it is very common and in fact happens in most instances that the final space left is insufficient to readily insert a single box and it is obviously a difficult matter to slide a box into such space on account of the rough sides which it is necessary to force in contact with the rough sides of the two boxes already on opposite sides of the space.

At present considerable time and labor is required where the space is slightly smaller than the box to go into the space and it is to relieve these disadvantages that my invention proposes a guide which may be readily inserted in place, will permit of quick easy insertion of the box in the final space, and which is both simple inexpensive and readily removable after use.

It is quite obvious that among the prerequisites of a guide of this nature, ready removability is of considerable importance and in proposing a guide, including a pair of slide plates, my invention contemplates the use of handles whereby the plates may not only be transported from place to place in a convenient manner, but may be readily withdrawn in a vertical direction after use and reinserted at a new point of use with facility and ease.

In the accompanying drawing which illustrates my present invention and forms a part of this specification,

Figure 1 is a perspective view showing a series of fruit boxes as they are packed, and illustrating the practical application of my invention,

Figure 2 is a vertical sectional view through one side of one of the boxes and showing one of the slide plates in connection therewith and also in section, and

Figure 3 is a top plan view of a portion of one of the boxes showing one of my slide plates in connection therewith.

Referring now to these figures and particularly to Figure 1 I have shown a series of fruit boxes 10 endwise upstanding in successive transverse rows just as they are placed within each tier of boxes in a refrigerator or other freight car for shipment and I have also shown a space which in practice results at the center of the car for the reception of the final box completing the tier, this latter box indicated at 11 being seen in course of disposition in place.

As above stated the boxes are packed in practice with the object of leaving at the center a space just sufficient to crowd the final central transverse row of which box 11 is the last, in place so that the entire tier will be so closely adjacent to one another as to defeat all danger of jostling or jolting of the boxes and consequently injuring the same and the commodity contained thereby.

In view of the slatted sides of the boxes and the fact that they bulge more or less this disposition of the final row is at the present time a tedious lengthy operation if the packing has been carefully done and the fact that it is so gives rise to careless packing at the ends of the car so as to leave ample space for the final transverse row and this when done allows for the undesirable jostling and jolting of the containers in transit.

The guide proposed by my invention for the ready insertion of the final transverse row of boxes where as intended the packing has been carefully carried out so as to leave just sufficient space for the tight packing of the final row, consists of a pair of slide plates which may be disposed vertically along the spaced opposing faces or sides of a pair of containers 10, these plates being indicated at 12 and having surfaces of which at least those turned toward one

another are smooth and unbroken in order to thus present surfaces between which the sides of the final box 11 may be forced and will more readily slide into place than 5 against the rough sides of the boxes 10 on opposite sides thereof if these sides were left exposed.

In order to guide the box 11 into place between the boxes 10 upon opposite sides 10 thereof, each of the slide plates 12 is provided along one vertical edge with outwardly flaring and slightly curved guide lips 13 in the form of lengthwise flanges between the lower portions of which one end 15 of the box 11 to be inserted in the space is initially forced as indicated in Figure 1.

At its upper edge each plate 12 has spaced upstanding lugs 14 supporting handles 15 substantially of ring shape, by means of 20 which the slide plates may be readily carried from place to place and easily inserted vertically along the opposing surfaces of spaced boxes 10 and readily pulled vertically between the surfaces of these boxes 25 and the opposite sides of the box 11 after the latter has been rocked upwardly and inwardly into place from the initial position of Figure 1.

Between the upstanding lugs 14 carrying 30 the handles 15, each plate has a lateral flange 16 terminating in a downturned edge 17 the latter of which thus provides for engagement over one of the end battens 18 of the boxes so as to prevent inward displacement of the slide plates toward one another while the box 11 is being inserted and yet permits of ready removal of the slide plates upwardly from their operative position after the box 11 has been inserted.

40 Each of the slide plates is also provided outwardly beyond its upstanding handle lugs 14 with laterally extended ears 19 adopted to rest upon the upper ends of the adjacent boxes 10, and these ears are preferably apertured in order to provide for the use of screws, nails or like fastening members in case the latter become desirable or necessary for the purpose of securing the slide plates temporarily in their effective 45 positions.

50 Thus where the ends of the car have been packed with the boxes 10 and the packing has proceeded to the point where but a single transverse series of boxes remains to be placed in order to complete the tier of boxes, the slide plates are used and inserted as previously described in order that this final series, box by box, may be inserted in place, and it is obvious that by the use of

55 a guide including the slide plates as described, this disposition of the final row may be accomplished with ease and facility where without the same the disposition of the final row would be tedious and difficult if as in a properly packed car the final space 60 will not permit of the insertion of the final row of boxes to slide freely between those boxes upon opposite sides thereof.

65 It is furthermore obvious my invention proposes a guide which is equally useful in the packing of boxes, baskets, crates, barrels and other forms of containers, as well as one which is simple, strong and durable and is not only economical as to first cost but will be practically free of cost of up- 70 keep thereafter.

I claim:

1. A guide to facilitate disposition of a commodity container between adjacent containers, consisting of a pair of slide plates 80 engageable with and extendible along the opposing faces of the adjacent containers, each having a smooth inner surface and a flaring guide lip alongside one side edge.

2. A guide to facilitate disposition of a commodity container between adjacent containers, consisting of a pair of slide plates 85 engageable with and extendible along the opposing faces of the adjacent containers, having outwardly flaring and curved 90 flanges along one side edge forming guide lips, as described.

3. A guide for the purpose described consisting of a pair of cooperating slide plates 95 having flanges along one side forming guide lips, and having upper handles for inserting the same into and withdrawing the same from, operative position.

4. A guide for the purpose described, consisting of a pair of cooperating slide plates 100 having upper handles and engaging ears and having flaring guide lips along one side edge.

5. A guide for the purpose described, consisting of a pair of cooperating slide plates 105 having flaring guide lips along one side edge and having upper handles and lateral extensions between the handles provided with downturned engaging edges.

6. A guide for the purpose described, consisting of a pair of cooperating slide plates 110 having flaring guide lips along one side edge and having upper handles and lateral extensions along the upper edges thereof adjacent to said handles, certain of said extensions having downturned engaging edges.

GEORGE L. COMLOSSY.
